RAILWAY TRAFFIC CONTROLLING SYSTEM

Carl F. Stoltz and Wilmer Welsh, Cincinnati,
Ohio, assignors to General Railway Signal
Company, Rochester, N. Y.

Application February 26, 1931, Serial No. 518,308

12 Claims. (Cl. 246—3)

This invention relates to traffic controlling systems for railroads, and more particularly to a system for the remote control of power-operated switch machines.

5 In a system of remote control of power-operated switch machines for use in connection with terminals, interlocking plants, and centralized traffic control systems, it is desirable to obtain the various controls and indications required for efficient operation of a switch machine over a minimum number of line wires between the tower or central office for each switch; and therefore, one object of the present invention is to provide a simple and reliable arrangement of line circuits 15 and relays by means of which several distinctive controlling and indication conditions may be transmitted or communicated instantaneously in response to the energization or de-energization of the line circuits.

20 More specifically stated, this invention provides for the transmission over two polarized line circuits of the controls required for a power-operated switch machine, and distinctive continuing indications of the presence of a train on the usual detector track circuit at the switch, the position of the switch points if over and locked, the operating or mid-stroke condition of the switch, and the presence of a train approaching the switch within certain approach locking limits.

25 Another object of the invention is to provide, in connection with the approach and detector locking usually employed with power-operated switch machines, an improved form of means for requiring movement of the control lever at the time the approach and detector locking is not effective, in order to operate the switch machine, so that the switch machine will not operate after a train movement over the switch until the operator shifts the control lever.

30 Various other characteristic features and advantages of the invention will be in part apparent and in part pointed out, as the description progresses.

In the accompanying drawing, the principles and functions of the invention are exemplified by one specific embodiment applied to a single switch, the various devices and circuits being illustrated in a simplified and diagrammatic manner, more with the object of making it easy to understand the nature and mode of operation of the invention, than with the purpose of showing in detail how the parts and circuits would be constructed and arranged in practice.

The stretch of track, with the single switch SW, and the signals 1 and 1A governing traffic in the facing direction over this switch, as shown in the drawing, are merely typical or representative of a simple facing-point switch layout; and it should be understood that the invention is applicable to the various switch and signal ar-

rangements, including crossovers, double-slip switches, movable-point frogs, with signals governing traffic in one or both directions, and the like, encountered in practice. The explanation of the invention, as applied to the simple single switch and signal arrangement illustrated in the accompanying drawing, will make clear to those skilled in the art how the principles, functions, and mode of operation of the invention may be applied to meet all other conditions encountered in practice.

The switch SW is intended to be operated by a suitable power switch machine, designated SM; and while this switch machine may be any one of the well-known types, it is assumed to be 15 of the electrically operated type, such as disclosed, for example, in the patent to W. K. Howe, No. 1,466,903, dated September 4, 1923. In accordance with this invention, the switch machine is supplied with operating current from a local battery 4, or other suitable source of direct or alternating current, in accordance with well-known practice. The application of operating current to the switch machine SM, over normal and reverse operating wires 5 and 6, is controlled 20 by a suitable polarized remote control relay WZ. If direct current is employed for the control of this switch machine, as in the particular embodiment illustrated, this control relay WZ may be of the well-known neutral-polar type; and if alternating current is employed for the control of the switch machine, this relay WZ may be any one of the well-known two-element alternating current relays. The specific construction of this control relay WZ is not material to the invention, its function being to shift the contact finger 25 7, or equivalent circuit controlling means, in response to reversals of the polarity of energization of a switch machine control circuit so as to select 30 the normal and reverse operating wires 5 and 6. 35

Associated with the switch SW are suitable point detector contacts, designated PD, which are operated, either as a part of the switch machine SM, or by separate connections to the switch points, in accordance with the position and locked condition of the switch points. One type of point detector, suitable for this purpose is shown and described in the patent to C. S. Bushnell, No. 1,517,236, dated November 25, 1924. As shown diagrammatically in the accompanying drawing, this point detector PD comprises four pairs of contact fingers 8—11, two movable contact blocks 12 and 13, and shunting contacts 14 and 15. When the switch points are over and locked in the normal position as shown, the pairs of contact fingers 10 and 11 are bridged by the contact blocks 12 and 13, the shunting contact 15 is closed, and the other shunting contact 14 is opened. When the switch points are unlocked or in midstroke, the contact blocks 12 and 13 are 55 60

automatically shifted to an intermediate position, out of engagement with all of the pairs of contact fingers 8-11, and both of the shunting contacts 14 and 15 are closed. When the switch points are over and locked in the opposite or reverse position, the other pairs of contact fingers 8 and 9 are bridged by the contact blocks 12 and 13, and the shunting contact 14 is closed, while the shunting contact 15 is open. A suitable source of current, such as the battery 16, and the pair of control wires 17 and 18 in combination with the contacts of the point detector PD, provide for the energization of a local switch repeating or signal selecting neutral-polar relay KR, with one polarity of current or the other, in accordance with the locked position of the switch points, and the deenergization and shunting of the relay KR, when the switch points are unlocked or in midstroke, as will be readily apparent to those skilled in the art, without tracing the circuits in detail.

The track rails of the stretch of track and the turn-out track, up to the fouling point for the switch SW, are provided with insulated joints and cross-bonding, in accordance with well-known practice, to provide the usual detector track circuit T-1, having a detector track relay 1T. This track relay 1T directly controls a repeater relay 1TP, over a circuit readily traced on the drawing from (+), indicating one terminal of a battery or other suitable source of current, through the front contact 20 of the track relay 1T, through the repeater relay 1TP to (-), indicating the opposite terminal of said source of current.

To simplify the illustration, many of the circuits on the accompanying drawing are illustrated in a similar conventional manner as terminating at (+), indicating a connection to one terminal of a suitable source of direct or alternating current, and at (-), indicating a connection to the opposite terminal of said source.

In accordance with the invention, it is contemplated that the track adjacent to the switch SW will be in practice provided with track circuits, wayside signals, line circuits, and the like constituting suitable approach locking for the switch. The specific details of such approach locking circuits are not material to the present invention; and as merely representative of such approach locking, the stretch of track at the left of the switch SW is shown conventionally as provided with two track circuits T-2 and T-3, having track relays 2T and 3T, the track circuit T-3 being in the rear of a distant or approaching signal 2, governing east-bound traffic toward the switch SW, and located braking distance in the rear of the signals 1 and 1A. A stick relay L, representative of an approach locking relay, is energized over a stick circuit through the front contacts 21 and 22 of the track relays 3T and 2T and its own front contact 23. This relay L has a pick-up circuit through the same front contacts of the track relays 3T and 2T and a back contact 24 of the detector track relay 1T. In this simplified arrangement, an east-bound train approaching the signal deenergizes the relay L and this relay L remains deenergized until this train has passed on to the detector track circuit T1. In the practical application of the invention, the approach locking will have other features of control by the indications of the signals, directional control, time release, and the like; but this simplified arrangement of the relay L will be sufficient to make clear to those

skilled in the art the nature of the present invention, and how the various types of circuits for complete approach locking protection, such as shown for example in the application of S. N. Wight, Ser. No. 120,423, filed July 3, 1926, may be employed in accordance with this invention.

The equipment in the tower or central control office, which is located at any desired distance from the switch SW, is diagrammatically illustrated in the left-hand part of the drawing, and comprises a suitable manually operable control lever LV for governing the switch machine SM; a portion of the usual track diagram which includes the switch SW, with an automatically operated miniature switch point to indicate the positions of the switch points if over and locked; relays KRP, LS and WL; and indicating lamps OS, TL, and HO.

The control lever LV is shown conventionally as comprising an operating handle 25, movable up and down to two extreme positions, corresponding to normal and reverse positions of the switch. This handle 25 is mechanically connected to movable contact fingers 26 and 27, co-operating with stationary contacts, indicated conventionally as arrows, in the normal and reverse extreme positions of the lever handle 25.

The indicator of the switch position, in the specific form shown, comprises a pivoted miniature switch point 28, positioned adjacent two wide lines 29 and 30 on the track diagram which represent the main track and turn-out track; and this miniature switch point 28 is connected to the armature 31 of two electro-magnets 32 and 33. When the electro-magnet 32 is energized, the armature 31 is attracted to the position shown, and shifts the miniature switch point 28 to the normal position shown; and if the other electro-magnet 33 is energized, the miniature switch point 28 is automatically shifted to the other reverse position.

The indicator for the detector track circuit T-1 is preferably a small indicator lamp OS, of the type commonly used on telephone switch boards, which is preferably located adjacent to the miniature switch point 28. A similar electric lamp indicator TL, preferably located adjacent to the control lever LV, when lighted in the manner hereinafter explained, indicates to the operator that the switch machine is not over and locked. This indicating lamp TL, conveniently termed a "transit light", is lighted while the switch machine is operating or in transit. A similar electric indicating lamp HO, also preferably located adjacent to the lever LV, is lighted in the manner hereinafter explained when there is a train on the detector track circuit, or a train approaching the switch under signal indications which make it unsafe to operate the switch. Since any movement on the part of the operator to control the switch machine under these conditions will be ineffective, the indication given by this lamp HO is conveniently termed a "hands-off" indication. These different indicating lamps OS, TL, and HO are caused to give distinctive indications either by reason of their color, or location, or both. If desired, other forms of electrically responsive indicators may be used instead of lamps.

The relay KRP, which is a repeater of the relay KR, is of the neutral-polar, or equivalent three-position type, of which the polar contacts 44 are of the magnetic stick type. This relay KRP is connected in an indication circuit, including line wires 35 and 36, which extends from the tower or control office to the point where the switch SW

is located. This indication circuit includes a front contact 31 of the detector track relay repeater 1TP, a front neutral contact 38 and a polar contact 39 of the relay KR, and one of the batteries 40 and 40^a. When the switch SW is over and locked in the normal position shown, and no train is on the detector track circuit, so that the relay 1TP is energized, then the relay KRP is energized with current of one polarity from the battery 40^a over a circuit readily traced upon the drawing through the polar contact 39 of relay KR to the right, neutral contact 38 of relay KR, front contact 37 of relay 1TP, line wire 35, relay KRP, line wire 36, back to the battery 40^a. This energization of the relay KRP with current of the normal polarity opens its neutral back contacts 42 and 43, and positions its polar contact 44 to the right. The relay KRP might be controlled directly by the point detector contacts PD, without the relay KR.

The relay LS is a stick relay of the usual neutral type, and is included in series in the switch control circuit which includes line wires 45 and 46, and extends from the control office to the switch. The relay WL is a slow-release relay energized by local circuits at the control office.

The various electrical connections between these various devices need not be specifically described, the various circuits involved in the operation being pointed out in the following explanation of the operation of the system.

Operation.—The parts and circuits are shown on the drawing in what may be termed the normal condition, corresponding with the switch SW over and locked in the normal position, and no trains adjacent to or approaching the switch. Under these normal conditions, the relay KRP is energized with positive polarity over the indication circuit 35—36, positioning its polar contact 44 to the right and establishing a circuit for energizing the operation electric magnet 32 from (+), polar contact 44 of the relay KRP, wires 15 and 16, magnet 32, to (—). With the contact 27 and the control lever LV in the same corresponding normal positions, relay WL is energized by the circuit from (+), polar contact 44 of relay KRP to the right, wires 15 and 47, lever contact 27 in the normal position, wire 48, relay WL to (—).

The switch machine control circuit, including wires 45—46, for energizing the relay WZ with normal polarity from the battery 50 in the central office, may be traced from the lower terminal of the battery 50, wire 51, lever contact 26 normal, wires 52 and 53, front contact 54 of relay LS, wires 55 and 56, relay LS, line wire 46, relay WZ, wire 51, front contact 58 of the detector track relay 1T, wire 59, front contact 60 of approach locking relay L, line wire 45, to the other terminal of the battery 50. The front contact 61 of the relay WL, together with the wires 62—55 and 63—53, forms a shunt for the front contact 54 of the relay LS.

In this normal condition of the system all of the indicating lamps OS, TL, and HO are extinguished.

Assume now that the operator desires to have the switch SW operated to its reverse position, and further that no trains are present to render it unsafe to operate the switch. The operator shifts the lever LV to the reverse position, moving the lever contact 26 to the dotted-line position and including the battery 50^a in the switch control circuit to energize the relay WZ with opposite polarity. During the movement of the

lever contact 26 from its normal to its reverse position, the supply of current to the switch control circuit 45—46 is momentarily interrupted, deenergizing the relay LS. Also, upon movement of the lever contact 27 to the dotted-line position, out of correspondence with the polar contact 44 of the switch repeater relay KRP, the relay WL is deenergized; but this relay WL is made sufficiently slow-releasing as to remain closed during the momentary deenergization of the switch control circuit, when the lever LV is shifted from one position to the other in an ordinary way. Consequently, the relay LS at once picks up as soon as the switch control circuit is energized with the reverse polarity.

The energization of the relay WZ with current of the reverse polarity establishes the reverse operating circuit for the switch machine SM, and since the approach locking relay L is assumed to be energized and its front contact 64 closed, the switch machine operates in the usual way to unlock the switch SW, shift its points to the reverse position, and again lock the points.

During this operation of the switch machine, when it is first unlocked, relay KR is deenergized, opening at its neutral contact 38 the indication circuit 35—36, and deenergizing the relay KRP. Under these conditions, the transit light TL is lighted over a circuit from (+), back contact 43 of relay KRP, wire 66, lamp TL, wire 67, front contact 68 of relay LS to (—). This informs the operator that the desired control has been transmitted to the switch machine and that it has commenced its regular operating cycle. When the switch machine SM completes its operation, and the switch points are locked in the reverse position, the relay KR is energized from the battery 16 through the point detector contacts PD with current of reverse polarity, closing its neutral contact 38, and shifting its polar contact 39 to the dotted-line position. This energizes the relay KRP with reverse polarity, opening its back contact 43 to extinguish the transit light TL, and shifting its polar contact 44 to the dotted-line position, in correspondence with the position of the lever contact 27, so that the relay WL is again energized. At the same time the electro-magnet 33 is energized to shift the miniature switch point 28 to the reverse position.

If, due to an obstruction in the points or for any other reason, the switch machine should fail to complete its operation, the relays KR and KRP remain deenergized and the transit light TL lighted. Consequently, if this lamp TL remains lighted for a time longer than ordinarily required for the switch to be operated, the operator knows that something is wrong and may return this switch to its normal position, and repeat the operation. The lighting of the transit light TL shows that the track switch is not over and locked in the position represented by the miniature switch point 28; but when this transit light TL is extinguished, the position of the miniature switch point 28 represents the existing position of the track switch in the field.

The same explanation is true for an operation of the switch from the reverse position to the normal position.

Assume now that the switch is over and locked in one position; that the signals 1 or 1A and the approach signal 2 have been cleared by the operator by controlling means not material to the present invention and not illustrated, and which may be of the type disclosed in the Wight application, Ser. No. 120,423 above mentioned,

and that a train approaches and passes over the switch. When this approaching train arrives within the approach locking limits, the relay L is deenergized. This opens the switch control circuit at the front contact 60 of the relay L and drops the relay LS, thereby lighting the lamp HO over a circuit from (+), lamp HO, wires 70 and 71, back contact 68 of relay LS to (-). In this way the operator is advised of an approaching train.

As the train in question advances and enters the detector track circuit T-1, the track relay 1T and the repeater relay 1TP are de-energized. The opening of the front contact 58 of the track relay 1T maintains the switch control circuit open and the relay LS is de-energized. The opening of the front contact 31 of the repeater relay 1TP breaks the indication circuit and de-energizes the relay KRP. In this way, the lamp OS is lighted over a circuit from (+), back contact 42 of the relay KRP, wire 72, lamp OS, wires 73 and 71, back contact 68 of relay LS, to (-). When the train leaves the detector track circuit, the switch control circuit and indication circuit are again established, and assuming that the lever LV has been left in a position corresponding with the position of the switch, so that the relay WL is energized, then both of the relays LS and KRP are energized and the lamps HO and OS are extinguished.

Assume now that, while an approaching train is within the approach locking limits, and the relay LS is deenergized to light the lamp HO, the operator should for some reason move the control lever LV to its other extreme position. This causes deenergization of the relay WL, since the lever contact 27 is then out of correspondence with the polar contact 44 of the relay KRP. Consequently, after the approaching train in question has passed and the approach locking is restored to normal, closing the switch control circuit at the switch, this circuit is maintained broken at the front contact 54 of the relay LS, since this relay LS cannot be energized with the relay WL deenergized. When this condition occurs, before the switch can be operated from its existing condition, the operator is obliged to restore the lever LV to its former position, in correspondence with the polar contact 44 of the relay KRP, so as to pick up the relay WL, and in turn permit the relay LS to pick up, whereupon the lever LV can be shifted to operate the switch to its other position.

The provision of the stick relay LS, having its pick-up circuit controlled by the relay WL, which is deenergized when the lever is not in a position in correspondence with the switch, assures that the control lever must be shifted by the operator after a train approaching the switch has passed. In other words, the manipulation of the lever LV required of the operator is substantially the same as if this lever were equipped with an electric lock restraining its movement when the detector and approach locking is effective. With this arrangement, no control tending to operate the switch to a different position can be transmitted from the control office to the switch location, when the presence of a train makes it unsafe to operate the switch, so that conditions cannot be set up by the operator for the switch to operate, and reliance placed entirely upon the control of the switch machine by the detector and approach locking to prevent an improper switch machine operation. This is considered to add to the protection against improper

switch machine operation by requiring co-operation of the operator with the automatic detector and approach locking. Also, if the operator should accidentally or carelessly shift the control lever LV with a train approaching, the switch cannot operate upon departure of the train to a position which the operator perhaps would not want. Moreover, with this arrangement, the operator is penalized for any attempt to shift the control lever LV, when it is improper to do so, because he is then required to shift the lever over and back to regain control of the switch machine.

From the foregoing, it can be seen that this invention provides for the direct line circuit control of a power-operated switch machine over one polarized line circuit, and for repeating by the relay KRP directly over a polarized line circuit the over and locked position of the switch points. It is evident that this switch repeater relay KRP, being directly and reliably controlled, may be utilized to select signal circuits, by means of electric connections in the tower or control office, in accordance with recognized practice in interlocking systems, in addition to operating the point indicator 28. This invention provides for the transmission, over these same line circuits, of indications of the occupancy of the detector track circuit, the presence of an approaching train rendering effective the approach locking, and the operating or mid-stroke condition of the switch machine, so that the operator has the necessary information of conditions at the distant switch location to control the switch and associated signals to the best advantage. These various features of the invention render it safe and practicable to govern from one tower or central control office the operation of any desired number of switches, located at any distance from such control point, with a minimum number of line wires, and through the agency of simple control levers, which do not require electric locks, indication devices, or mechanical locking.

Various additions, modifications, and adaptations may be made in the particular construction and arrangement of parts and circuits shown and described without departing from the principles and mode of operation characterizing the invention.

What we claim is:

1. In a traffic controlling system of the character described, a power-operated switch, a polarized control circuit for governing the operation of said switch, a polarized indication circuit having its continuity and polarity governed in accordance with the locked condition and extreme positions of said switch, a detector track circuit interrupting both of said circuits, a relay at a distant control point included in each of said circuits, and means controlled by said relays for giving distinctive continuing indications of the presence of a train on the detector track circuit, the locked or unlocked condition of the switch, and the position of the switch if over and locked.

2. A system of control and indication for power-operated switches comprising, a polarized control circuit and a polarized indication circuit extending from a central control office to each switch, means responsive to a train approaching the switch and breaking the control circuit, means for breaking the indication circuit when the switch is unlocked, a detector track circuit, means controlled by said track circuit for interrupting both said control circuit and said

indication circuit, and indicating means in said control office selectively responsive to the interruption of either or both of said circuits for giving distinctive continued indications of the presence of a train on the detector track circuit, an approaching train and the unlocked condition of said switch.

3. A system for controlling power-operated switches comprising, a polarized control circuit for controlling a switch machine for operating a track switch, a stick relay having its winding in said circuit and also governing its continuity, circuit controlling means responsive to the position of the switch, a control lever for controlling said circuit, and means for restoring said stick relay only if said control lever is in a position corresponding with the position of said circuit controlling means.

4. In a system of the type described, the combination with a power-operated track switch, a polarized control circuit for governing the operation of said switch, a control lever for controlling the energization of said circuit, means associated with said lever for indicating the position of said switch, a track circuit controlled means at the switch for breaking said control circuit under conditions of traffic unsafe for operation of the switch, and means associated with said lever and governed by said indicating means for maintaining said control circuit open upon movement of the lever to a position out of correspondence with the existing position of the switch at a time when said circuit is opened by said track circuit controlled means, said last mentioned means also maintaining said control circuit closed if it is closed at the time of such movement of the lever.

5. In a traffic controlling system of the type described, the combination with a control lever and a polarized control circuit for governing the operation of a distant power-operated switch machine, indicating means responsive to the position of said switch, track circuit controlled means at the switch for interrupting said circuit, a stick relay included in said control circuit, a pick-up circuit for said stick relay, and a slow-releasing relay for governing said pick-up circuit and having its energization dependent upon the correspondence between the position of said lever and the position of said switch indicating means.

6. A system for protecting the operation of power switch machines comprising, the combination with a control lever and a polarized control circuit for governing the operation of the switch machine, track circuit controlled means at the switch for interrupting said circuit, and means for maintaining said circuit open if the control lever is moved to a position out of correspondence with the position of the switch when said circuit is interrupted including a stick relay and its stick contact in series in said circuit and a contact closed for a definite short time following movement of said lever for shunting said stick contact, said definite short time being independent of the rate of movement of said lever.

7. A system for protecting the operation of power switch machines comprising, the combination with a control lever and a polarized control circuit for governing the operation of the switch machine, track circuit controlled means at the switch for interrupting said circuit, a stick relay and its stick contact included in series in

said circuit, and means for shunting said stick contact responsive to a circuit portion closed only when said lever and said switch machine assume corresponding positions.

8. A system for protecting the operation of power switch machines comprising, the combination with a control lever having a normal and a reverse position and a polarized control circuit for governing the operation of the switch machine, track circuit controlled means at the switch for interrupting said circuit, a stick relay and its stick contact included in series in said circuit, and a slow acting relay for shunting said stick contact for a short period of time following movement of said lever.

9. A system for protecting the operation of power switch machines comprising, the combination with a control lever and a polarized control circuit for governing the operation of the switch machine, track circuit controlled means at the switch for interrupting said circuit, and a slow acting relay energized only when said lever and said switch machine assume corresponding positions for controlling the continuity of said circuit.

10. A system for protecting the operation of power switch machines comprising, the combination with a control lever and a polarized control circuit for governing the operation of the switch machine, track circuit controlled means at the switch for interrupting said circuit, and a slow acting relay for controlling the continuity of said circuit and actually energized only when said lever and said switch machine assume corresponding positions but maintaining the continuity of said circuit for a predetermined time after such correspondence has been discontinued.

11. A system for protecting the operation of power switch machines comprising, the combination with a control lever and a polarized control circuit for governing the operation of the switch machine, track circuit controlled means at the switch for interrupting said circuit, and a slow acting relay energized only when said lever and said switch machine assume corresponding positions, and assuming its deenergized position a short period of time after such correspondence has been discontinued for controlling the continuity of said circuit.

12. In a centralized traffic control system for railroads, a track switch, a switch machine for operating said track switch, a switch control relay for governing said switch machine, a control lever, a polarized control circuit connecting said control relay and said control lever, approach locking means associated with said track switch for opening and closing said polarized control circuit in accordance with traffic conditions, an approach lock repeating relay having windings included in said polarized control circuit and associated with said control lever for indicating the condition of said approach locking means, and means including said lock repeating relay for requiring said control lever to be in correspondence with said track switch subsequent to the opening of said polarized control circuit by said approach locking means before said control lever can again govern said switch control relay.
